UNITED STATES PATENT OFFICE

HOWARD F. GORSUCH AND EMIL WICKSTROM, OF GALION, OHIO, ASSIGNEES TO THE HUGHES-KEENAN CO., OF MANSFIELD, OHIO, A CORPORATION OF OHIO

END GATE FOR DUMP WAGONS OR TRUCKS

Application filed April 26, 1923. Serial No. 634,854.

The present invention relates to an end gate for dump wagons or trucks and has for its principal object to provide a gate which may be converted into a chute when it is desired to empty or dump the wagon or truck.

Other objects of the invention are to provide a convertible end gate of this nature which is simple and efficient in construction, reliable in operation, inexpensive to manufacture, readily operated, durable, and well adapted to the purpose for which it is designed.

With the above and numerous other objects in view as will appear as the description progresses, the invention resides in certain novel features of construction and in the combination and arrangement of parts as will be hereinafter more fully described and claimed.

In the drawing,

Figure 1 is an elevation of the end gate embodying our invention, showing the outer side thereof,

Figure 2 is a fragmentary detail perspective thereof,

Figure 3 is a side elevation of the gate showing the same converted into a chute, and

Figure 4 is a detail perspective showing the bolt operating mechanism.

Referring to the drawing in detail it will be seen that there is a frame for the gate which consists of the side members 1 and the top member 2. The side members 1 are preferably formed of angle irons while the top member 2 is in the form of a plate connecting the two side members 1 at their upper ends. A shaft 3 pierces the side members 1 adjacent their upper ends and brackets 4 mounted on the top member 2 also receive this shaft. This shaft 3 is provided for mounting the device on the open end of a wagon body (not shown) and thus the gate is pivoted from its top end so that the bottom end may be swung outwardly from the wagon. Any suitable means may be used for locking the gate in position in respect to the wagon body and as such means are common in the art it has not been

thought necessary to disclose the same herein.

As is evident from the above description the frame is open except for its side and top members. The opening in the frame is normally closed by a plate 6 which is constructed at its sides with members 7 in the form of angle irons which receive a shaft 8 which is journaled in suitable brackets 9 carried at the lower ends of the side members 1. The plate 6 is disclosed in a closed position in Figures 1 and 2 and in an open position in Figure 3. A pair of hinged panels 10 are disposed in the opening of the frame A and are normally held in a closed position, such as is indicated in Figures 1 and 2, by spring hinges 11, which are shown in the drawing in dotted lines; and since such hinges are of conventional construction no detailed illustration or description thereof seems necessary.

In order to hold the plate 6 in a closed position, a pair of bolts 12 are slidably mounted in openings 13 (Fig. 2) in members 7 and are adapted to pass through openings 14 in side members 1. Links 15 connect these bolts 12 with the lever 16 which is actuated by a rod 17 and hand lever 18 pivoted on one of the members 7. As this mechanism is shown in Figure 1 it will be seen that by fulcruming the lever 18 the bolts 12 may be withdrawn from the apertures 14 and the plate 6 may then swing on shaft 8 to the position disclosed in Figure 3 in which position it will be held by bracket members 20 (which are foldable so as to be out of the way when the gate is closed). Suitable stops 21 are provided on the plate 6 so that when the panels 10 are opened they will abut these stops and be substantially at right angles to the frame, thus forming an efficient chute through which the contents of the wagon body may pass. The pressure from the contents of the wagon, especially during dumping, will keep the side panels 10 open.

It is thought that the operation and utility of the device will be evident without a further detailed description. We have, in the present instance, shown and described

the preferred embodiment of the invention which will give in practice satisfactory and reliable results, and it is to be understood that the same is susceptible of modification in various particulars without departing from the spirit or scope of the invention or sacrificing any of its advantages.

Having thus described our invention what we claim as new is:—

- 10 1. The combination with a vehicle body, a pair of pivotally mounted side bars at one end of the body, said bars being hinged at their upper ends to swing in vertical planes, a gate pivoted to said bars near their lower ends, and means on the gate adapted to lock the gate to the bars, and a panel hinged to each side bar inwardly of the gate to swing in a horizontal plane.
- 15 2. The combination with a vehicle body, a pair of pivotally mounted side bars at one end of the body, said bars being hinged at their upper ends to swing in vertical planes, a gate pivoted to said bars near their lower ends, and means on the gate adapted to lock the gate to the bars, and a panel hinged to each side bar inwardly of the gate to swing in a horizontal plane.
- 20 3. The combination with a vehicle body, a pair of pivotally mounted side bars at one end of the body, said bars being hinged at their upper ends to swing in vertical planes, a gate pivoted to said bars near their lower ends, and means on the gate adapted to lock the gate to the bars, and a panel hinged to each side bar inwardly of the gate to swing in a horizontal plane, said panels being arranged to flatly engage the inner surface of the gate for being held in
- 25 40 closed position by the gate when the latter is locked to the bars.
- 30 35 4. An end gate of the class described including an open frame pivotally mounted at its upper end to swing in a vertical plane, a panel hinged to each side of the open frame to swing in a horizontal plane, a plate hinged to the bottom of the frame for closing the opening thereof, means on the plate and engageable with the frame for holding the plate in a closed position, means for supporting the plate in open position wherein it is substantially on a level with the bottom of the dump body, said supporting means being associated with and carried by the plate and the frame, and stops on the plate adapted to be abutted by the panels when in open position.
- 45 50 5. The combination with a vehicle body, a pair of side bars pivotally mounted at their upper ends on one end of the body, slots in said bars, a gate pivoted to said bars near their lower ends, and means on the gate adapted to enter said slots to lock the gate to the bars, and a panel hinged to each

side bar inwardly of the gate to swing in a horizontal plane.

6. The combination with a vehicle body, a pair of side bars pivotally mounted at their upper ends on one end of the body, slots in said bars, a gate pivoted to said bars near their lower ends, and means on the gate adapted to enter said slots to lock the gate to the bars, and a panel hinged to each side bar inwardly of the gate to swing in a horizontal plane, and means to normally yieldingly swing said panels to closed position.

7. The combination with a vehicle body, a pair of side bars pivotally mounted at their upper ends on one end of the body, a gate pivoted to said bars near their lower ends, a panel hinged to each side bar inwardly of the gate to swing in a horizontal plane, and means on the gate adapted to lock the gate to the bars.

8. An end gate of the class described including a frame having an opening and pivotally mounted at its upper end to swing in a vertical plane, and members carried by and movable with the frame and positionable for closing the opening of the frame or for forming a chute associated therewith, said members embodying a panel hinged to each side of the frame to swing horizontally and a plate hinged to the lower end of the frame to swing vertically, and means to lock the plate to the frame for maintaining the plate and the panels in position to close the opening of the frame.

In testimony whereof we affix our signatures.

HOWARD F. GORSUCH.
EMIL WICKSTROM.
